JUICE EXTRACTOR OR SIMILAR ARTICLE

Harold Weiss, Fort Lee, N.J., assignor to Van Wyck
International Corporation, New York, N.Y.

Filed Apr. 5, 1971, Ser. No. 131,567

Term of patent 14 years

Int. Cl. D7—04

U.S. Cl. D7—48

FIG. 1

FIG. 2

FIG. 1 is a front perspective view of a juice extractor or similar article showing my new design;

FIG. 2 is a bottom plan view thereof;

FIG. 3 is a rear elevational view thereof;

FIG. 4 is a side elevational view thereof; and

FIG. 5 is a top plan view thereof.

I claim:

The ornamental design for juice extractor or similar article, as shown.
